METHOD AND DEVICE FOR THE WINDING OF ELASTIC THREADS

Louis Boucraut, Troyes, France, assignor to Societe a responsabilite limitee La Maillé Souple, Paris, France

Application November 26, 1946, Serial No. 712,318
In France November 22, 1945

Section 1, Public Law 690, August 8, 1946
Patent expires November 22, 1965

3 Claims. (Cl. 242—45)

1

The employment of elastic threads and especially threads of covered rubber, has so far been made hard owing to the fact that these threads, that are reeled with a more or less uneven tension, leave the spool in a series of jerky motions when being unwound and reach the spot where they are to be used sometimes slack and sometimes unduly stretched.

What happens is that the woven material manufactured out of this covered rubber contains rubber threads of uneven tension that cause the formation of hollows and lumps in the fabric and militate against an attractive appearance.

The object of the present invention is to obviate the foregoing disadvantages. To this end, it aims at a method of unwinding and feeding elastic threads that includes the placing between the feed-spool and the working loop of a device that provides a low and steady tension in place of the highly erratic pull on the thread. The invention also has for its object a device for the operation of the above mentioned method. This device comprises a drum with a completely smooth facing on which the thread, as it leaves the feed-spool, is coiled up with several extra windings. Between this drum and the working loom a reserve stock of thread is arranged under the form of a free length of thread tensioned in the shape of a V by a light floating weight that, on the one hand, regulates the steady low tension demanded and on the other hand, controls the checking or free-running of the drum, according as the height of the V made by the thread becomes less, under the influence of an increase in tension of the thread, or becomes greater through a lessening of this tension caused by a pull of the thread on the feed-spool by the checked drum.

From a practical point of view, the floating weight may consist of a ring that is set to slide freely along an upright guide-rod; at a fixed position in its travel this ring strikes against a member that controls the checking or free-running of the drum; this member is for instance, in the form of a swinging lever and constitutes a switch in an electric circuit used for the checking or release of the drum. In accordance with one method of execution of the device in line with the invention, the checking and release are secured by means of an electro-magnet the armature of which comes into action for changing the position of the loosely mounted drum on its axis urging one side of the drum into frictional engagement with the side of a pulley that is keyed on the same axis and driven continually by the loom.

2

When the tension of the thread increases, the ring is drawn upwards and strikes against the lever that closes the control circuit for the engagement of the drum; the drum commences to spin at high speed, it draws the thread from the feed-spool and feeds it in the direction of the ring at a much higher rate than the working speed. At this juncture, the tension becomes less and the ring comes down again until the lever has swung in the opposite direction and thus actuates the release and the consequent pulling up of the drum.

A method of execution of the device in accordance with the invention is illustrated as an example in the accompanying drawings:

Figure 1 is a diagrammatic elevational view of this device.

Figure 2 is a plan view corresponding to Figure 1.

The elastic thread 1 unwound from the spool 2 passes over a guide 3 and is coiled in several turns on a light drum 4, then it goes through the ring 5 that may travel freely up and down the vertical slide-way 6, then through a lead 7 and it is then drawn along 8 towards its working position. A perforated scale, that is not shown in the diagrammatic drawing, keeps each turn of thread apart on the surface of the drum in order to avoid any over-riding tendency. When this drum is idle, the loom draws the thread and takes up the available stock of thread that forms the V between 4 and 7. If the tension of the thread increases, the ring 5 is pulled upwards and strikes against the end of the small lever 9, that swings around pivot 10; the other end of this lever drops, thus making the contact at 11.

The contact 11 energizes the electro-magnet 12 that attracts the end of a lever 13, swinging around pivot 14, while the other end of the lever 40 15 urges the drum 4 against the pulley 16 that is furnished with a leather washer 17; this pulley 16 is revolved continually by a belt 18 from the loom.

The pulley 16 drives then in its turn the drum 45 4 that draws the elastic thread from the spool 2, at a speed much above working speed; this thread is fed to the ring 5 that immediately sinks down along its slide-way 6, while moving away from lever 13. The latter, swinging, breaks the contact 11; the electro-magnet 12 is no longer energized and releases the lever 13; the drum 4 draws away from the pulley 16 and ceases rotating. As soon as the reserve stock of thread between 4 and 7 is again used up, the same procedure carries on and another stock is made up.

The thread thus is kept under a tension corresponding to the weight of the ring 5 and accordingly is fed to the loom under steady tension, that may be as low as desired, since it depends solely on the weight of the ring.

What I claim is:

1. In a device for unwinding and feeding threads and more particularly threads of covered elastic rubber from a feed spool on to a working loom, the combination of a loosely rotatable and transversely shiftable drum arranged between the spool and loom and over which the thread is adapted to be coiled through several turns, driving means for the drum operable from the loom, means for shifting the drum into and out of frictional engagement with the driving means, a light weight adapted to act on the thread between the drum and the loom, and to assume a level in accordance with the length of the floating stock of thread existing between the drum and loom and means controlling the shifting of the drum in accordance with the level assumed by the light weight.

2. In a device for unwinding and feeding threads and more particularly threads of covered elastic rubber from a feed spool on to a working loom, the combination of a loosely rotatable and transversely shiftable drum arranged between the spool and the loom and over which the thread is adapted to be coiled through several turns, driving means for the drum, means for shifting the drum into and out of engagement with the driving means, a ring engaging the thread between the drum and the loom, a substantially vertical rod over which said ring is slidably mounted for assuming a level corresponding to the length of floating stock of thread existing between the drum and loom, an electric circuit, a switch in said circuit, and a lever controlling

5

said switch under the control of the vertical location of the ring.

3. In a device for unwinding and feeding threads and more particularly threads of covered elastic rubber from a feed spool on to a working loom, the combination of a loosely rotatable and transversely shiftable drum arranged between the spool and the loom and over which the thread is adapted to be coiled through several turns, means for positively driving the drum, means for connecting and disconnecting last mentioned means with reference to the drum, a ring engaging the thread between the drum and the loom, a substantially vertical rod over which said ring is slidably mounted for assuming a level corresponding to the length of floating stock of thread existing between the drum and loom, an electric circuit, and electro-magnet in said circuit for controlling the connecting and disconnecting means, a switch in said circuit, and a lever controlling said switch and positioned adjacent the vertical rod and in the path of movement of the ring so as to be automatically operated by the ring.

LOUIS BOUCRAUT.
